UNITED STATES PATENT OFFICE.

HARRY G. KAUFMAN, OF NEW YORK, N. Y.

DESIGN FOR A RING.

Application filed September 7, 1922. Serial No. 3,638. Term of patent 3½ years.

To all whom it may concern:

Be it known that I, HARRY G. KAUFMAN, a citizen of the United States, residing in New York, in the county of New York and State of New York, have invented a new, original, and ornamental Design for a Ring, of which the following is a specification, reference being had to the accompanying drawing, forming part thereof, in which—

Figure 1 represents a top plan view of a ring embodying this design.

Figure 2 is a side view of the same.

I claim:

The ornamental design for a ring as shown.

HARRY G. KAUFMAN.

Witnesses:

HENRY B. OTTENBERG,
RUDOLPH A. NICOLOSI.
